UNITED STATES PATENT OFFICE.

OSCAR A. FORSBERG, OF CHICAGO, ILLINOIS, ASSIGNEE TO CRANE COMPANY, OF CHICAGO, ILLINOIS, A CORPORATION OF ILLINOIS.

SAND-BLAST APPARATUS.

1,419,130.

Specification of Letters Patent. Patented June 13, 1922.

Application filed April 16, 1921. Serial No. 461,947.

To all whom it may concern:

Be it known that I, OSCAR A. FORSBERG, a citizen of the United States, residing at Chicago, in the county of Cook and State of Illinois, have invented certain new and useful Improvements in Sand-Blast Apparatus, of which the following is a specification.

This invention relates to sand blast apparatus for sand-blasting bathtubs, bowls, and the like, and in fact, any cast articles which are required to be sand-blasted for the purpose of smoothing their surfaces prior to the enameling operations.

Prior to my invention, it has been customary in many plants to dispose these articles in a room or chamber into which an operator enters with the sand-blast nozzle attached to a flexible hose, and the operator directs the blast from this nozzle against the surfaces to be operated upon. This operation, however, is very injurious to the health of the operator, since the dust and fine sand particles with which the room

becomes quickly filled are very injurious to the tissues of the lungs and throat, with the result that an operator is unable to continue at this work for any prolonged period of time.

One of the primary purposes of my present invention is to provide a machine for performing this work, which will be entirely automatic in its operation, so that the articles are operated upon in a chamber or housing in which it is unnecessary for the operator to enter, as the articles are automatically fed into and out of the chamber, and the blasting operation is performed in the chamber entirely automatically and without necessity of either manual manipulation or inspection within the chamber.

Another purpose of my invention is to provide an apparatus which will distribute the sand under pressure over the various surfaces of the articles to be operated upon, the nozzles in order to effect this result being movably mounted within the housing, and mechanism being provided which automatically moves the nozzles to vary their direction of discharge so that all of the surfaces of the articles are subjected to the blasting operation before the articles are delivered from the chamber.

Another feature of my invention resides in the fact that the sand is not only auto-

matically delivered to the blasting nozzles, but this sand is subsequently collected, subjected to a vacuum action to remove the dust and light particles of sand, and is then screened to free it from pieces of iron and other large particles, and after being cleaned and screened, the sand is automatically returned to the hopper for subsequent delivery to the nozzles again, so that by my apparatus, the same sand may be repeatedly used in the blasting operation.

A further object of my invention is to provide an apparatus of the character indicated, which shall be simple in construction, compact in arrangement, and efficient, reliable and durable in operation.

For the purpose of facilitating an understanding of my invention, I have illustrated one preferred embodiment thereof on the accompanying drawings, from an inspection of which the invention and many of its inherent advantages should be readily understood and appreciated.

Referring to the drawings:

Fig. 1 is a plan view of an apparatus embodying my invention;

Fig. 2 is a longitudinal sectional view through the apparatus shown in Fig. 1;

Fig. 3 is a fragmentary view on a large scale showing the upper nozzle mountings;

Fig. 4 is a vertical sectional view through the machine on the line 4-4 of Fig. 2;

Fig. 5 is an enlarged detail view of the lower nozzles and their mountings;

Fig. 6 is a similar view looking toward the left at Fig. 5.

While my apparatus may be mounted and arranged in any convenient manner and location, it is preferable for convenience in handling the articles, that the feed end of the apparatus be disposed substantially at the floor level, and the delivery end elevated somewhat above the floor level so that the articles, after being shaken free from the molding sand, may be disposed on the apparatus without lifting, and will be delivered from the apparatus onto trucks, by which they are transported to the enameling room, or other desired location. In the present instance, therefore, reference character 7 indicates the floor of a shop or molding room, which is provided with a pit or depression 8, in which a portion of my apparatus is disposed, so as to position the feeding or intake end 9 of the conveyor sub-

stantially level with the floor 7, thus permitting the bathtubs or other articles to be operated upon to be readily placed upon the conveyor without undue lifting.

5 The apparatus comprises suitable framework arranged to support the lower track, consisting of the rails 11 and also the upper track, consisting of the rails 12, upon which the endless conveyor, indicated generally by

10 reference character 13, is adapted to travel. This conveyor comprises a series of side links pivotally connected together by transversely disposed axle rods 14, upon which are mounted the rollers 15 shaped to travel

15 on the tracks. These rods serve as the supports upon which the articles to be sand-blasted, are carried, and since, as will be later apparent, these rods travel across the path of the blasts of sand, I found it preferable as a matter of protection to these rods, to dispose upon each a tube or sleeve 16, which shields the rods from the wearing action of the sand, and since the sleeves are loosely rotatable upon the rods, the surfaces

20 exposed to the sand blasts are continually changing, thus prolonging the life of the sleeves, as well as the rods. At the intake, or feed end of the machine, the carrier is trained over a pair of pulleys or sprocket

25 wheels 17, and at the delivery end, similar wheels 18 are provided, this end of the conveyor being mounted upon suitable standards or supports 19 at the requisite height to deliver the articles upon trucks which are

30 positioned at the end of the conveyor to receive the articles. The conveyor may be driven in any suitable manner, and one convenient method is to employ a drive chain 21, which is trained over a sprocket wheel

35 fixed upon a shaft 22, upon which the carrier wheels 18 are fixedly mounted. In order to maintain the proper position of the conveyor between its supporting end wheels, the track 12 is inclined throughout a considerable portion of its length, as shown in Fig.

40 2, and the track 11 is also inclined throughout a portion of its length and suitably shaped to guide the lower lap of the conveyor in its travel.

45 The conveyor, between its ends, passes through a housing 23, which is of suitable shape, for the purposes hereinafter indicated, this housing being preferably made of sheet metal and lined with wood, or other lining which is well adapted to resist the destructive effects of the sand blasts. The receiving end of this housing is provided with inwardly swinging doors or sealing flaps 24 (Fig. 1) and similarly, the delivery end is

50 equipped with similar doors 25, which however, open outwardly so that the articles 26, shown in the present instance as bathtubs, which are moved through the housing, automatically open these sealing flaps or doors

55 in their travel and prevent the escape of any

appreciable amount of sand- and dust-laden air from the housing.

Within the housing, above the conveyor and sufficiently above to clear the articles 26 in their travel, I have mounted a plurality 70 of sets of blasting nozzles, indicated generally by reference character 27. The upper portion of the housing is shaped, as shown in Fig. 2, to provide vertical walls, between which these nozzles are mounted, and as 75 shown in Figs. 2 and 3, the nozzles proper are carried by a pipe 28 mounted to oscillate in bearings in these walls and are also equipped with pipes 29 which travel in slots 31 formed in the walls. 80 The pipes 29 are connected by a flexible hose to any convenient source of compressed air (not shown) which may be either a compressor, or preferably, a tank, in which the requisite air pressure is confined. The 85 supporting pipes 28 are each connected by its respective hose 31 to the bottom of a sand hopper 32 mounted above the housing and from which sand is supplied through the hose 31 and the pipes 28 to the nozzles. 90

It will be apparent from Fig. 2 that the sets of nozzles are spaced apart longitudinally of the machine and are disposed at different elevations, and from Fig. 4, that each set comprises two or more nozzles 95 spaced apart transversely of the machine, and all mounted to deliver downwardly and inwardly against the upper and lateral surfaces of the articles 26 disposed on the carrier. The nozzles are adapted to be oscillated about the pipe 28 as an axis so as to vary their direction of discharge substantially between the positions shown in full and dotted lines respectively in Fig. 4, and for the purpose of effecting this oscillatory movement of the nozzles, I have provided a constantly driven shaft 33, which is equipped with a plurality of eccentrics 34 connected by links 35 to lever arms 36 fixed to the shafts 28 at one side of the machine. 100 A downwardly depending arm 37 is connected by a transverse connecting rod 38 with another arm 39 fixed to the pipe 28 at the other side of the machine so that the nozzles at both sides of the machine are simultaneously operated from one eccentric 34. Both sets of nozzles disposed at different elevations, as shown in Fig. 2, are therefore operated from their respective eccentrics, with the result that the blasts of sand under 110 pressure are distributed over the exposed surfaces of the articles to be operated upon as these articles travel longitudinally through the housing across the paths of discharge from the various nozzles.

115 For the purpose of operating upon the downwardly exposed surfaces of the articles which are not reached by the upper nozzles 27, I have mounted beneath the conveyor, another set of nozzles 41 provided with a 120

125

130

series of discharge tips 42, which are supplied with sand from a plurality of pipes 43 each connected at one end with the nozzle body and at its other end with a hose 44 leading to the sand hopper 32. Air is supplied to these nozzles to pipes 45 connected at their outer ends with hose attached to the source of compressed air, previously mentioned. The nozzles 41 are also adapted to oscillate transversely of the apparatus, and one preferred form of mounting is shown in Figs. 5 and 6, from which it will be observed that outside the walls 46 of the housing, I have mounted supporting bearing brackets 47 in which rest the depending bearing members 48 of the coupling heads 49, and a lever 51 rigidly connected with one of the coupling heads, connected by a link 52 to a bell crank lever 53 outside the housing, which 10 in turn is actuated by a link 54 connected with an eccentric 55 on the shaft 33, as shown in Fig. 2. Apertures 56 are provided in the walls 46, as shown in Fig. 6 to permit of the oscillatory movements of the coupling 25 heads 49 and the pipes and nozzles carried thereby.

It will be apparent that all of the nozzles, both above and below the conveyor, are supplied with sand and with air under pressure 30 to deliver blasts of sand against the surfaces of the articles on the conveyor, and that all of the nozzles are oscillated back and forth within limited arcs so that the directions of the blasts delivered thereby are 35 continuously varied, thus insuring that all of the surfaces of the articles will be reached and operated upon by the blasts. As the articles are slowly conveyed through the housing across the paths of discharge of 40 the various nozzles, all of the surfaces, side and end, as well as top and bottom, are subjected to the action of these blasts entirely automatically and without any manual manipulation or supervision or inspection by 45 the operator with the result that the operator is relieved of the injurious effects of the sand- and dust-laden air, and furthermore, the automatic operation is much more rapid, efficient and satisfactory, and produces more 50 uniform and better results than can be secured with the customary hand manipulation of a blast nozzle.

It will be apparent from Fig. 4 that the conveyor rollers 15 are protected from the 55 destructive effects of the sand by inclining the walls 55 of the housing inwardly immediately above the conveyor, and preferably, a substantial seal is effected between these walls and the conveyor by flexible sealing 60 strips 56. Similarly, the walls below the conveyor are inturned, as indicated at 57 and are provided at their edges with sealing strips 58, as shown. The lower lap of the conveyor is entirely protected from the sand 65 by the inverted V-shaped bottom wall 59 of the housing, which divides and diverts laterally the sand which descends from the upper portion of the housing, the sand being delivered through conduits 61 into downwardly tapering passages 62 which deliver 70 at their lower ends into elevator chambers 63, in which elevator belts 64, equipped with the usual buckets, are mounted to elevate the sand from the bottom of the apparatus and return it to the hopper 32, as will be apparent from Fig. 2.

For the purpose of screening the sand and freeing it from particles of iron, nails, and other foreign matter, the upper ends of conduit 61 are equipped with screens 65, as 80 shown in Fig. 4. For the purpose of freeing the sand from dirt, dust, and fine broken sand particles, I have provided within the housing beneath the nozzles, downwardly inclined converging suction conduits 66, the 85 opposed ends of which have a restricted passage 67 between them, through which the sand must fall. These conduits are connected at their sides with suction flues 67 through which suction is applied to the conduits, with 90 the result that the sand flowing in a narrow sheet between the opposed ends of these conduits, is freed from dirt and small particles so that only the clean and effective sand is returned to the hopper for future use. 95

It will be apparent from the foregoing that my apparatus is designed to automatically sand-blast any articles which are loaded onto the conveyor, and that the only attention required is in the placing of the 100 articles on one end of the conveyor and the removal of them from the opposite end. The articles during their passage through the machine are thoroughly sand-blasted on all of their surfaces, and the sand is then 105 collected, air cleaned, screened, and then returned to the hopper for further use. It is believed that my invention, its construction, mode of operation, and many of its advantages will be understood from the foregoing 110 without further description, and while I have shown and described, for purposes of illustration, a preferred embodiment of the invention, obviously its details of structure may be varied within wide limits without 115 departing from the spirit of the invention as defined in the following claims.

I claim:

1. In a sand blast apparatus, the combination of a chamber, an endless conveyor arranged to travel through said chamber in an upwardly inclined direction and adapted to carry the articles to be treated, a plurality of sets of sand blast nozzles arranged in said chamber above said conveyor, a plurality of 120 nozzles arranged in said chamber beneath the conveyor, means for oscillating all of said nozzles so as to direct their discharge in planes intersected by the articles on the carrier, means for supplying sand and air under 125

pressure to said nozzles, and doors at the ends of the chamber adapted to normally close the chamber and to be opened by the articles in their travel.

5 2. In a sand blast apparatus, the combination of an enclosed sand blast chamber, a conveyor adapted to carry articles through said chamber in an inclined position, a plurality of sets of nozzles mounted in said 10 chamber laterally of and above the path of travel of articles on the conveyor, means for oscillating said nozzles so as to deliver the discharge therefrom against the sides and upper faces of the articles, means for supplying sand and air under pressure to said nozzles, and means for collecting the discharged sand.

3. In a sand blast apparatus, the combination of a sand blast chamber, means for conveying the articles to be treated through said chamber from end to end thereof, a plurality of nozzles disposed laterally of and above the path of travel of the articles and adapted to discharge against said articles, a plurality of 25 nozzles mounted beneath and substantially centrally of the conveyor, means for supplying sand and air under pressure to all of said nozzles, and means for oscillating the nozzles so as to distribute the discharge over the 30 surfaces of the articles.

4. In a sand blast apparatus, the combination of a sand blast chamber, a conveyor extending therethrough and adapted to convey articles to be treated through said chamber, 35 sand blast nozzles arranged above, laterally of, and beneath the conveyor to deliver against the exposed faces of the articles on the conveyor, mechanism for imparting an oscillatory movement to said nozzles to increase the effective area of discharge, and means beneath the nozzles for cleaning the discharged sand and delivering it laterally of and out of contact with the lower lap of said conveyor.

45 5. In a sand blast apparatus, the combination of an elongated chamber, an endless conveyor extending therethrough and adapted to convey articles to be treated through the chamber, a plurality of sets of nozzles mounted above the conveyor, a plurality of nozzles

mounted below the conveyor, means for oscillating all of said nozzles, means for delivering sand and air under pressure to said nozzles, means for cleaning the discharged sand, and means for returning said sand to the 55 nozzles.

6. In a sand blast apparatus, the combination of a chamber, a conveyor extending therethrough, a plurality of nozzles disposed above said conveyor, a plurality of nozzles beneath said conveyor, said last-named nozzles comprising a plurality of parallel pipes rigidly connected together and mounted to oscillate about a common center, and means for oscillating all of said nozzles. 65

7. In a sand blast apparatus, the combination of a chamber, a plurality of pipes disposed within said chamber, nozzles attached to each of said pipes, means for rigidly connecting said pipes together, a pivotal support for said connecting means about which said pipes and nozzles oscillate around a common axis, means for supplying sand and air under pressure to said pipes, and means for oscillating the pipes and nozzles carried thereby. 75

8. In a sand blast apparatus, the combination of a housing, a conveyor extending therethrough in an upwardly inclined direction, yieldable closures for the ends of said housing adapted to be intermittently opened 80 by articles carried on the conveyor, a plurality of sets of downwardly directed nozzles arranged within said housing at different elevations to discharge against the surfaces of the articles disposed on the conveyor, a plurality of upwardly directed nozzles, means for oscillating said nozzles, and means for supplying sand and air under pressure to the nozzles. 85

9. In a sand blast apparatus, the combination of a housing, a track extending therethrough, sand blast nozzles arranged in said housing, means for supplying sand to said nozzles and a conveyor arranged to travel on said track, said conveyor comprising transversely extending axle rods, rollers thereon, and tubes surrounding said rods between said rollers for protection to said rods. 90 95

OSCAR A. FORSBERG.
